UNITED STATES PATENT OFFICE.

ERNST FREDRIK NORDIN, OF GOTTFENBORG, SWEDEN.

CYLINDER LOCK.

Application filed May 20, 1919. Serial No. 298,357.

To all whom it may concern:

Be it known that I, ERNST FREDRIK NORDIN, a subject of the King of Sweden, residing at Gottenborg, in the county of Gottenborg and Bohus and Kingdom of Sweden, have invented new and useful Improvements in Cylinder Locks, of which the following is a specification.

Safety locks, hitherto have been subject to certain disadvantages in that they could be opened by smashing the glass, in the door or by making a hole in the door in some other way for the purpose of inserting the arm and opening the lock of the door from the inside. Another disadvantage of such previous types of locks is that they cannot be deadlocked from the inside, and consequently they may always be opened from the outside by anyone, who has the proper key to the lock. Again, if such locks should get out of order their mechanism could not be taken apart and inspected, without removing the whole lock from its place in the door.

This invention has for its object to overcome the inconveniences mentioned and is characterized principally therein, that the lock-cylinder proper, which in a known way is enclosed in a casing and provided with a locking device of guard plates may in case of repair be removed by simple means, without removing the whole lock. In addition the lock is so arranged as to be bolted by means of a special key from the inside as well as from the outside, so that it cannot be opened from its opposite side with any other key than the proper bolting-key. Further the lock-cylinder is prolonged outside the casing and the projecting portion thereof is provided with additional bolts designed to be operated by means of the ordinary key, and which bolts when in locking position enter a projection on the lock-casing proper. Finally the improved lock is provided with a guiding plate or partition wall, positioned within the nest of guard plates and has for its object to guide the key, so that the key will be afforded a steady support, when rotated.

Reference will now be made to the accompanying drawings, illustrating two embodiments of the invention, wherein Fig. 1 is an elevational view of a cylindrical lock, from that side of the lock, which faces the room to be closed by the lock, Fig. 2 shows the

same lock, as viewed from the outside of the room, Fig. 3 shows the same view as Fig. 2 but with the outer cover of the lock-casing removed and the lock partly in section, Fig. 4 is a perspective view of the removable cover of the lock-casing, Fig. 5 shows the inside of the lock with the lock-cylinder or lock-mechanism removed, Fig. 6 is a side elevation of the arrangement shown in Fig. 2, 65

Fig. 7 is a respective detail of the lock cylinder,

Fig. 8 is a respective detail of the internal fastening ring,

Fig. 9 is a section through the lock with 70 the key applied,

Fig. 10 is a similar view with the inner or bolting key applied and with the outer key removed,

Fig. 11 is an elevational detail of the 75 guiding plate,

Fig. 12 illustrates another embodiment of the lock designed as a common so called mortise-lock or door-lock with the cover of the casing removed, 80

Fig. 13 is a similar view showing the sliding bolts in operative position, and

Fig. 14 shows the same lock in section viewed from above.

In the drawings 1 indicates a casing, in 85 which a frame 4, fitted to the sides 2 and 3 of the casing and provided with a bolt 5, is reciprocable. The frame 4 and the bolt 5 are held in locking position, that is to say with the bolt 5 projecting outside the casing, by means of one or several spiral springs 8, provided between the wall 6 of the casing 1 and the side 7 of the frame 4, said springs being guided by a pin 9, passing through the frame side 7. The outer side 90 of the casing 1 is covered by a lid 10, fastened with screws, and in the embodiment shown in Figs. 1-12 provided with a projecting socket 11 and which has for its purpose together with a socket 12, screwed on the rear 100 side of the casing, to retain and to guide the lock-cylinder 13, which, in order to be held in position between the sockets 11 and 12, is provided with a shoulder 14.

The lock-cylinder consisting of a cylindrical socket, provided with a bottom 15, contains in a known manner a plurality of thin plates so called guard plates 16^a, 17^b, 18^c, etc., provided with notches for the key-bit, between which plates a plurality of sliding- 110

bolts 21, 22, 23, are operated by means of an outer or ordinary key 20, said sliding-bolts having portions 24, 25, 26, which, when moved outwardly, bolt the lock-cylinder to the frame 4 as well as to the cylindrical portion 11 of the cover 10 by means of notches arranged therein. The sliding bolts 21, 22, 23, co-operate with a curved plate-spring 101 (Figs. 12, 13) by means of prongs 102, 10 on the bolts, so that these are retained in raised position by means of the prongs 102 resting on the rounding of the spring 101. One (or several) of the sliding bolts 21, 22, 23 for instance the bolt 22 has the same 15 width beneath its prong 102 as the other sliding bolts, so that in its raised, withdrawn position (Fig. 12) the bolt is retained by the spring 101 but is of a narrower width than the other bolts 21, 23 above said prong 102 so as to be able to freely pass the spring 101, when the last-mentioned sliding bolts are lowered (Fig. 13). A partition wall 27 positioned between the plates 16 has for its object to limit the way of inserting of the 20 key into the lock as well as to guide the key during its rotation in the lock. The partition wall 27 is provided with a hole 34 and with a projection 35, which during the rotation of the key 20 or 30 is respectively embraced by a notch 45 or 46 in the key bit. All guard plates 16^a, 16^b, 16^c etc., are fastened mutually and in the cylinder 13 by means of screws 31, 32, which are screwed in the bottom 15 of the cylinder. In the lock- 25 cylinder there is also provided a hole 33 for a common spindle handle to be rigidly mounted in the cylinder (Figs. 1-3, 7). The handle spindle may also be applied in a hole 103 (Figs. 12, 13,) in a hub 105, provided with a member 104, which hub 105 may be journaled in suitable openings in the casing and by means of its member 104 engages a corresponding notch in the frame 4 to withdraw the bolt.

40 The lock is mounted in such a way, that the projecting cylindrical socket 11 enters the material of the door and thus becomes invisible.

45 The operation and application of the lock 50 is as follows:

When the door, provided with the lock, is to be locked, the locking-bolt 5 on closing the door will first be pressed into the casing 1 against the action of the spring 8 and then 55 will be projected behind a keeper-plate in the door-case, intended for the locking-bolt. To now lock the door from the outside the key 20 is put into the key-hole 39 with the bit turned upwards, that is, it is put into the 60 upper half of the key-hole and is there rotated half a turn in the direction, shown by the arrow in Fig. 1. The key may now be removed through the lower half of the key-hole 39.

65 By rotating the key 20 against the pres-

sure of the spring 101, the latter acts against the prongs 102 so that the bolts 24, 25 and 26 will be moved outwardly from the cylinder 13, the bolt 24 entering the frame 4 while the bolts 25 and 26 pass through the cylindrical portion 11 of the cover 10 (see Fig. 8) preventing the revolving of the lock-cylinder, and by reason of the lugs 37 the bolt 5, is prevented from reciprocating. On the other hand, if it is desired to unbolt the 70 door the key 20 is inserted into the lock in the position just described, that is, with the bit projecting downwardly and is rotated one half turn to the right so as to lift the 75 sliding bolts upon the curved spring 101 thus 80 releasing the lock-cylinder to allow it to revolve freely.

The lock, when not bolted, may be opened in a known way by pressing down the handle spindle, inserted in the hole 33, thereby 85 rotating the lock cylinder 13 which retracts the bolt against the action of the spring 8.

By means of a special key 30 the lock may be bolted from the inside, that is from the 90 side opposite that mentioned above by inserting said key with its bit turned upwardly and rotating the same one half a turn. This key is so short, that it actuates only the sliding bolt 21 with the part 24 but not the 95 bolts 22, 23 with the parts 25, 26 (Fig. 9). As long as the bolt 21 is in the locking position, thus caused by the key 30, the key 20 on account of the position of the sliding bolt 21 and disalignment of the key sweeps in the 100 bolts cannot be turned, and thus the lock can not be opened from the outside.

If the handle spindle according to Fig. 13 is provided with a separate part 105 instead of with the lock-cylinder proper the frame 4 105 is operated by the member 104, when said handle is rotated, bringing with it the lock-cylinder 13 in case the same is unbolted, as shown in Fig. 13. The present invention has the following advantages over previous types 110 of cylindrical locks.

The cylinder 13 with its mechanism may be easily removed from the lock, for which purpose it is only required to unscrew the 115 socket 12. The keys 20, 30 obtain a steady guide by the projection 35 of the partition wall 27 and are thus protected from excessive wear. The locking effect is increased with the increased number of sliding bolts, since in addition to the part 24 directly co-operating with the lock-casing, the parts 25, 26 co-operate with the projection 11, the 120 number of which last-mentioned parts can be increased at will by using more sliding bolts. By replacing the lock plates, which are quite identical concerning their outlines, the character of the lock may completely be altered and while said replacing may be 125 achieved after the easy removing of the cylinder 13, just mentioned, is it possible to 130

alter the lock quickly, so that it becomes inaccessible for the ordinary key, if the latter should accidentally come into the possession of an unauthorized person. The partition 5 wall 27 may also be applied on different places between the lock plates, thereby altering the character of the lock.

The arrangement according to Figs. 12, 10 13, with the sliding bolts held by the spring 101 makes the lock practically burglarproof, because, if anyone should try to poke the bolts upwardly with a picklock and succeeds in lifting one of them, so that it is supported by the spring 101 common to all of the bolts 15 at a point below the prong 102, this sliding bolt will fall down again, since, by the raising of next lock-plate the prong 102 of said plate pushes aside the spring 101, as it passes by this spring.

20 Having thus particularly ascertained and described the nature of my said invention and in what manner the same is to be performed, I declare that what I claim is:

1. A safety lock including a casing, an in- 25 side cover plate for the casing having an opening therein, a frame slideable in the casing, a locking bolt projecting from the frame, a duplex key operable lock cylinder rotatable in the frame and operably connect- 30 ed with the frame so that when locked the frame is prevented from sliding, means for releasably retaining the lock cylinder in the frame so that it is inaccessible from the outerside of the lock when the lock is in po- 35 sition on a door but may be readily removed through the opening in the inside cover plate without disturbing the casing or the position of the frame and bolt and means for sliding the frame when the cylinder is unlocked to re- 40 tract the bolt.

2. A safety lock including a casing, a frame slideable in the casing, a lock bolt carried by the frame and designed to be projected through the casing, a duplex key op- 45 erable lock cylinder rotatable in the frame and containing a plurality of slideable bolts and a plurality of lock plates separating the bolts, the bolts being all adapted to be actuated by means of a key insertable from the 50 outer side of the lock while only one or part of the bolts are adapted to be actuated by means of a key insertable in the inner side of the lock, whereby the lock when the last mentioned bolts are brought into locking po- 55 sition can be actuated by the ordinary key with the object of bolting the lock from the outer side, means for operably connecting the lock-cylinder with the frame so that when the lock-cylinder is locked the frame 60 is prevented from sliding, means for releasably retaining the lock-cylinder in the frame so that when the lock is in position on the door it is inaccessible from the outerside of the lock but may be readily removed from

the inner side without disturbing the cas- 65 ing or the position of the frame and bolt, and means for sliding the frame when the cylinder is unlocked to retract the bolt.

3. A safety lock as claimed in claim 2 whereon the sliding bolts are provided with 70 prongs, and a curved plate-spring common to all the said bolts for cooperating with all of the prongs on the bolts to normally hold the bolts in bolting position.

4. A safety lock as claimed in claim 2 75 having a partition wall arranged between the lock plates and serving as a support for the key during the rotation thereof.

5. A safety lock as claimed in claim 2 whereon the retaining means for the lock- 80 cylinders includes a plate on the outside of the casing inaccessible from such side when the lock is in position on a door and a re- movable socket on the innerside of the lock- casing for cooperating with the plate and 85 being accessible from the inner side so as to be removed to permit the removal of the lock-cylinder.

6. A safety lock as claimed in claim 1 whereon the frame is provided with a plu- 90 rality of notches, lugs on the lock-cylinder for cooperating with certain of the notches in such manner that when the cylinder is in a locked position sliding of the frame is prevented but being designed to permit of 95 a limited sliding movement of the frame when the lock-cylinder is unlocked, a han- dle-spindle rotatable in the lock-casing and in engagement with the frame for sliding the frame and spring means for normally 100 projecting the frame and bolt.

7. A safety lock including a casing, a frame slideable in the casing, a locking bolt projecting from the frame into the casing, a duplex key operable lock rotatable in the 105 casing and normally engageable with the frame to partially rotate with the frame during the sliding of the latter and designed to be removably locked to the frame to prevent movement of the frame, means for 110 sliding the frame when the lock is released and means for normally holding the bolt extended.

8. A safety lock as claimed in claim 7 in which the frame is provided with notches 115 and wherein the means for sliding the frame consists of a handle-spindle rotatable in the casing and an arm projecting from the spindle and engageable with the rotation to cause a sliding of the frame upon the 120 rotation of the spindle.

In testimony whereof I have affixed my signature in presence of two witnesses.

ERNST FREDRIK NORDIN.
